UNITED STATES PATENT OFFICE.

GEORGE SINCAK, OF BRIDGEPORT, CONNECTICUT.

COMBINED WINDOW AND TRANSOM.

1,375,186.

Specification of Letters Patent. Patented Apr. 19, 1921.

Application filed June 10, 1920. Serial No. 387,898.

To all whom it may concern:

Be it known that I, GEORGE SINCAK, a citizen of the United States, residing in the city of Bridgeport, county of Fairfield, and 5 State of Connecticut, have invented certain new and useful Improvements in Combined Windows and Transoms; and I do declare the following to be a full, clear, and exact 10 description of the invention, such as will enable others skilled in the art to which it appertains to make and use the same.

This invention relates to certain new and useful improvements in a combination window and transom, and it has for an object 15 to provide a novel construction of upper sash embodying a transom section which is hinged on the upper edge of the upper sash body whereby said transom part may be opened for the purpose of ventilation irrespective of the sash.

The invention further resides in an improved transom operating mechanism designed for supporting a window shade whereby the latter will not interfere with 25 the opening of the transom and will be disposed out of the wind so that it will not be blown and flapped thereby.

In the drawings:

Figure 1 is a vertical fragmentary section 30 of the improved window construction depicting the transom operating mechanism in side elevation; and

Fig. 2 is a front elevation of the mechanism and a fragment of the transom window.

Referring more in detail to the drawing, the numeral 1 designates the lower sliding sash and 2 the upper sliding sash to the upper or top rail of which is hingedly connected, as at 3, the transom 4 which may be 40 considered as a component part of the upper sash and is slidable therewith. The outer lower edge of the transom is downturned into an overhanging lip 5 which functions as a water shed for the joint between the 45 transom and the top rail of the upper sash.

The transom operating mechanism is carried by the upper sash and consists of a link 6 pivoted at one end to the transom and at its opposite end to a collar 7 which is fixed 50 on a vertically slidable rod 8. This rod is slidable through a vertical bearing 9 of the bracket 10 and is provided on its inner side with a vertical series of notches or seats 11 in which a pawl or plunger 12 is adapted to 55 have selective engagement. The pawl is yieldably projected into the bearing 9, being

backed by a coiled spring 13 within a socket 14 communicating with said bearing. The bracket is secured to the upper sash in proximity to the transom and is provided with a shade seat 15 for receiving one trunnion or bearing of the shade 16, the opposite end of the shade roller being supported in a companion transom lifting mechanism, or merely a shade bracket alone, disposed on the opposite side of the window. A stop collar 17 is fixed on the upper end of the operating rod 8, to prevent accidental withdrawal of the same from its bearing, while a guide ring or collar 18 is secured to the window 70 jamb 19 to slidably embrace the lower end of the rod immediately above the finger piece 20.

The operation is obvious from the foregoing, since to obtain the desired ventilation 75 the transom is opened by pulling down on the rod 8. When the transom is thus opened and both sashes locked together the two sashes may be moved upwardly as a unit to provide a small ventilating opening at the 80 bottom through which an intruder cannot gain entrance because the sashes are locked together and may not be moved independently of one another.

On the other hand, if the sashes are unlocked each may be shifted independently of each other, and without the shade becoming entangled. Furthermore the shade is hung from the upper sash so that it will never be opposite an opening for being 85 blown and flapped by the wind. The construction is simple and easily operated, the transom being retained at a predetermined angular adjustment by the yieldable pawl. When the upper sash is moved vertically, 90 the rod 8 will merely slide in its fixed guide 18 while the remainder of the mechanism 95 bodily moves with the sash.

What is claimed is:

1. A window construction including a 100 slidable upper sash, a transom hinged to the top rail thereof, a combined shade bracket and rod guide fixed on the sash and formed with a shade seat and an outwardly disposed vertical bearing, a rod slidable in the 105 bearing and formed on its inner side with a series of notches, a spring pressed pawl in the bearing for engaging in the notches to hold the rod adjusted, a link connection between the transom and the rod, and a second 110 guide for the rod fixed to the window jamb.
2. In a window construction including a

slidable upper sash, a transom hinged to the top rail thereof, a combined shade bracket and rod guide fixed on the sash and formed with a shade seat and an outwardly disposed vertical bearing, a rod slidable in the bearing and formed on its inner side with a series of notches, a spring-pressed pawl in the bearing for engaging in the notches to hold the rod adjusted, and a link connecting 10 the transom to the rod.

3. A window construction including a slidable upper sash, a transom hinged to the top rail thereof, a combined shade bracket and rod guide fixed on the sash and formed 15 with a shade seat and an outwardly disposed vertical bearing, a rod slidable in the

bearing, means for holding the rod adjusted, and means for connecting the rod to the transom.

4. A window construction including a 20 slidable upper sash, a transom hinged to the top rail thereof, and means carried by the sash for opening the transom.

5. A window construction including a 25 slidable upper sash, a transom hinged to the top rail thereof, a combined shade bracket and rod guide fixed on the sash, and means connected to the transom and operating through the guide for opening the transom.

In testimony whereof I affix my signature. 30

GEORGE SINCAK.
